UNITED STATES PATENT OFFICE.

WILFORD A. HILL, OF WALTHAM, MASSACHUSETTS, ASSIGNOR OF TWO-THIRDS TO ELMER E. BUTMAN, OF SAME PLACE, AND GEORGE W. LAWRENCE, OF CROMWELL, CONNECTICUT.

POWDER-FOLDING MACHINE.

SPECIFICATION forming part of Letters Patent No. 529,908, dated November 27, 1894.

Application filed September 8, 1893. Serial No. 485,076. (No model.)

To all whom it may concern:

Be it known that I, WILFORD A. HILL, of Waltham, in the county of Middlesex and State of Massachusetts, have invented certain new and useful Improvements in Powder-Folding Machines, of which the following is a specification.

The object of this invention is to provide a machine which will fold medicinal powders in papers in the same manner as they are folded by hand, and to this end the invention consists in certain novel features of construction and combination of parts hereinafter described and claimed.

The accompanying drawings illustrate a construction for carrying out the invention. Figure 1 shows a side elevation of a machine embodying the invention. Fig. 2 shows a front elevation of the machine. Fig. 3 shows a vertical longitudinal section. Figs. 4, 5 and 6 show section views which illustrate the steps in the folding operation. Figs. 7 and 8 show respectively a perspective view and a sectional view of a folded powder. Figs. 9 and 10 illustrate a device for dumping the powder, Fig. 9 being a side elevation, and Fig. 10 a section. Fig. 11 is a section on line 11-11 of Fig. 2, looking in the direction of the driving disk, the latter being in position with one of the racks about to engage with the spur wheel on shaft *c*.

The letter *a* designates the supporting frame of the machine and *b* a hopper supported thereby in an elevated position and adapted to contain the powder. A vertical shaft *b'* in the hopper carries stirring arms *b²* and a feed-screw *b³*, and the said shaft is adapted to be turned by a bevel gear *b⁴*, formed with a hub in which the hopper fits, and to which the shaft is pinned. A continuation *b⁵* of the hopper forms a bearing for a shaft *c*, which is formed with a cavity *c'* for receiving and measuring the dose of powder. The shaft in its normal position stands with the cavity *c'* on the upper side where it may be filled with powder from the hopper, and the shaft is adapted to be rotated so as to invert the cavity and dump the powder therefrom. The shaft carries a gear *c²* as

50 a means of receiving rotary motion, and

transmits motion to the gear *b⁴* by means of a segment *c³* affixed to it, and meshing with said gear.

A block *c⁴* forms the bottom of the cavity *c'*, and may be adjusted to vary the size of the cavity for different doses. The means here shown for adjusting the block consists in a rod *d* supported eccentrically in the shaft *c*, and against which the block bears so that by turning the said eccentric rod the block may be moved in the cavity and the depth thereof varied. A knob *d'* connected to the end of the rod *d* by means of a spindle *e⁹* provides means for turning the latter, and said knob will be marked to indicate different doses, and by registering these marks with an index-finger *d²* the proper adjustment of the block *d* can be determined. The block is preferably spring actuated against the eccentric rod by means of springs *e¹⁰*, one of which is shown in Fig. 10.

Means may be employed to project the block and clear the cavity of powder when it reaches the dumping position, as follows, (see Figs. 9 and 10:) An indicator arm *e* is mounted loosely on the stem of the rod *d*, and projects over the periphery of the knob *d*, and is provided with a set-screw *d³*, to fix it at different points determined by a scale on the knob. To adjust the block *c⁴* the knob is turned until the arm *e* abuts against a stop *e'* projecting from the end of shaft *c*. A gear *e²* is fixed on the stem of the knob and a segment *e³* is adjustably fastened to the frame, and is designed to remain fixed at one position while the machine operates. The said gear being eccentric to the shaft, *c*, when the latter is rotated the center of said gear describes an orbit and some of its teeth will encounter the segment *e³*, and the rod *d* will project the block *c⁴* and cause it to clear the cavity of powder. A spring *e⁴* returns the block *d*.

The means for projecting the block *c⁴* as just described may be dispensed with, and the block set in its adjusted position by means of a screw *c¹⁰* having a head *c¹¹* as shown in Fig. 1, said screw being fitted to a hole in the shaft *c* and bearing against the end of the block *c⁴*.

The paper 2 of which the powders are

formed is carried in a roll and is fed in a continuous strip by feed-rollers f and f' , the latter being supported in pivotal bearings and spring actuated against the former, and the 5 roller f carrying a gear f^2 as a means of receiving motion. A chute g is supported in a position to receive the paper from the feed rollers and guide it to the cutter and folders. The cutter is composed of two members, the 10 stationary one of which, h is carried by pivoted arms h' , and pressed down by springs h^2 . The other member h^3 of the cutter is carried on a bar h^4 , which constitutes a folder as will hereinafter appear, and is pivoted to 15 the frame of the machine, its center of movement being at the point h^5 . Said bar h^4 carries a segmental side-piece h^6 which supports the knife h . A bar i is fixed to the frame of the machine in such a position that the bar 20 h^4 may abut against it in its normal position with its outer or top side flush with the edge of the bar i , and when the bar h^4 is turned forward on its pivot a corner is formed in which the paper is creased, as hereinafter explained. A bed j is fastened to the frame of the machine at a point below the bar i , and is cut out at the middle to form a depression j' . A folder-plate j^2 projects from a bar j^3 which is pivoted to the frame of the machine, so as 25 to bring the axial line at the lower edge of the bed j , at which place the paper is creased. The bar j^3 carries a pair of curved fingers j^6 extending parallel with the plate j^2 . Guides k are connected with the frame, on opposite 30 sides of bed j , by hinges k' , and are held by springs k^2 in position to receive the paper from the chute g . The bar j^3 carries fingers j^4 which are arranged to abut the guides k , and throw them outward clear of the edges 35 of the paper.

A folding bar or plate m is pivoted to the frame so that it may normally have position below the bed j , and said bar and bed are beveled, and their edges meet at a corner 40 where a fold is made in the paper. The bar m carries wipers m' at opposite sides, which wipers have a quadrant shape, and in their normal position have their straight edges flush with the bar h^4 and bed j . These wipers 45 turn down the ends of the folded paper by passing the ends of the bed j .

The operation is as follows: The feed-rollers feed the proper length of paper out of the chute g , and over the bed j and folder j^2 , said 50 paper being confined in the guides k at each side. The said folder j^2 moves over to the position shown in Fig 4, thus folding the paper, as the latter is held in the guides k , and said folder stops long enough to allow the 55 shaft c to dump the powder contained in the cavity c' . This charge of the powder falls into the bite of paper formed by the folder j^2 and is accommodated in the depression j' in the bed j . The folder j^2 is carried on and folds 60 the paper down upon the bed j , and at the same time the knife h^3 advances far enough

1 to cut the paper in coaction with the knife h . Then the knife h^3 recedes sufficiently to allow the edge of the paper to fall back under it and against the bar h^4 . This bar advances again, 70 and the edge of the paper being held by engagement with the knife, a crease will be formed between the bar h^4 , and the stationary bar i . The folder h^4 folds down the paper sufficiently to bring its edge under the fingers 75 j^6 , and then returns to its normal position, leaving the paper. The folder m is turned outward on its pivot and carries the paper over onto the bed j , a crease being formed between the edges of the said folder and the 80 bed, and the fingers j^6 directing the part folded by the bar h^4 , upon the body of the paper. At the same time the wipers m' pass the ends of the bed and turn down the ends of the folded paper. 85

It will be seen by reference to Fig. 6 that the paper has been doubly folded, and that the part 3 containing the powder is under the folder plate j^2 while the other part 4 is on top of said plate, and the ends 5 extend past the 90 bed j . The folders m and j^2 return to their normal positions, and the plate j^2 carries the folder over and delivers it.

The guides k are moved out of the path of the knife h^3 , and folder m by fingers j^4 on the 95 bar j^3 .

It will be seen that the powder is folded exactly as it is customary to do it by hand, one edge of the paper being folded over the other 100 as seen at 6, Fig. 8.

The means here shown for imparting motion to the parts at the proper times consist in a disk o having mutilated teeth in its inner side adapted to engage the gears f^2 and c^2 , and gears h^9 and j^9 and m^9 , on the journals of the 105 folders, at the proper time.

The rows of teeth projecting from the disk constitute racks, and they will be so termed. Referring to Figs. 1, 3 and 11, particularly the latter, it will be seen that the racks are 110 adapted to engage with the gears or pinions as follows: rack o' with gear c^2 ; rack o^{10} with gear f^2 (the teeth of rack o^{10} are longer than those of rack o' , the latter passing by the side of gear f^2); racks o^{11} and o^{12} with opposite 115 sides of gear h^9 to rotate it alternately in opposite directions; racks o^{13} and o^{14} with opposite sides of gear m^9 , racks o^{15} and o^{16} with opposite sides of gear j^9 .

It is evident variations may be made in the 120 structure here illustrated, and hence the invention is not limited in this respect.

Having thus described my invention, what I claim as new, and desire to secure by Letters Patent, is—

1. A powder-folding machine comprising in its construction paper feeding mechanism, a pivotal folder for forming the fold which receives the powder, a cutter which severs the piece of paper and also constitutes a folder 130 for making the fold which carries one edge of the paper over the other, a final folder and

end-wiper, and means for actuating the above named parts in their proper order.

2. A machine of the character described comprising in its construction paper feeding mechanism, a primary pivoted folder for making the fold which receives the powder, a pivoted cutter for severing the piece of paper, said cutter constructed to serve as a folder to carry one edge of the paper over the other, and a final pivoted folder having wipers to turn the ends of the folded paper.

3. A machine of the character described comprising in its construction guides for holding the paper, a pivoted folder for making the fold which receives the powder, said folder having projections which act against the guides and move them free of the paper, a combined cutter and folder, and a final folder and end-wiper.

4. A machine of the character described, comprising in its construction a bed, a primary pivotal folder adapted to make the fold which receives the powder and carrying curved fingers, a pivotal folder adapted to make the fold which carries one edge of the paper over the other, and a final pivoted folder which carries the folded paper under the

curved fingers on the primary folder and doubles the paper upon the bed.

5. A machine of the character described, comprising in its construction a hopper; and a rotatable shaft therein, carrying stirring arms and a feed-screw below said stirring arms, mechanism for discharging a pre-determined quantity of powder from said hopper, mechanism for feeding intermittently a continuous strip of paper, a cutter for severing the paper, folders for turning the sides and ends of the severed paper, and means for intermittently operating the several parts.

6. In a powder-folding machine, the combination with feed-mechanism, pivotal folders, and a cutter, each having a gear or pinion on its journal of a disk having mutilated teeth for actuating the gears or pinions in their proper order.

In testimony whereof I have signed my name to this specification, in the presence of two subscribing witnesses, this 31st day of August, A. D. 1893.
